CLOSURE

William J. Keith, Brookline, Mass., assignor to
 Keith-Peabody, Inc., Brookline, Mass., a corpora-
 tion of Massachusetts

Application August 3, 1942, Serial No. 453,437

3 Claims. (Cl. 215—43)

1

This invention relates to an improvement in closures, particularly for bottles, jars, or other containers of the type adapted to be removably attached thereto as by screw threads or other means of fastening a closure on the container.

It has been proposed heretofore to construct closures with parts thereof of non-metallic material, such as paper, cardboard or the like, but such materials have required reenforcing with metal parts, either by a metal hood over the outside thereof or a metal ring inside the wall of the closure, to obtain the necessary strength and rigidity and to provide for the secure fastening of the closure on the container.

It has been proposed also to form closures entirely of such non-metallic materials as plastic resins which contain phenolic compounds, but such materials are critical during the present war emergency and not readily available for the manufacture of closures for containers. The metals, such as tin and steel, used heretofore for the reenforcing of paper or other closures, are also critical materials not readily available for this purpose.

The object of this invention is to construct the closure entirely of non-critical material, such as paper or the like, while at the same time effecting a secure rigid structure capable of being fastened tightly on a container, for removal therefrom, so as to seal the contents of the container effectively, and which closure is durable, inexpensive to manufacture, is of light weight, and lends itself to decoration or ornamentation in an effective manner.

This closure is formed preferably both with a side wall and guide ring formed of paper or other thin non-metallic material that may be wound in multiple layers, with the upper edge of the side wall turned inward and supporting a top disc thereon, while a liner has its periphery received between the inturned portion of the side wall and the upper edge of the guide ring when it is securely held in place thereby and presents a neat appearance at the inner side of the closure.

The guide ring is formed by winding a thin strip of non-metallic material, such as paper, into a multiplicity of layers to provide the desired thickness, and by adhesive or otherwise securing the layers together. The guide ring is wound up of rigid form which will add strength to the closure and provide a detachable connection for the container which enables the closure to be applied thereto repeatedly, if desired.

The invention is illustrated in a preferred em-

2

bodiment, together with modifications thereof, in the accompanying drawing in which:

Fig. 1 is a vertical sectional view through a closure embodying this invention;

Fig. 2 is a bottom plan view thereof;

Fig. 3 is a detail cross section through a modified form thereof; and

Fig. 4 is a similar view through a still further modified form thereof;

The invention is shown as applied to the sealing of containers, such as glass bottles, jars or the like, of the character designated generally at C, and having a neck C1 at the open end thereof which is externally screw-threaded to receive a closure thereon that seals the inlet and outlet for the container.

The closure embodying the present invention is preferably constructed of paper or like non-metallic material throughout, sufficient rigidity being provided by building up portions of the closure by means of laminations which are adhesively secured together to form a rigid unitary structure. The several laminations are exaggerated considerably in the drawing for clearness of illustration, it being evident that in an actual construction, many more laminations will be used than are shown in the drawing, and of materially thinner composite structure.

The closure is constructed of a top or cover disc 1, which may be formed of cardboard, or laminated paper, as described, of sufficient thickness and with the laminations adhesively secured together so as to form a rigid top structure for the closure. The top disc 1 is shown as extending throughout the area of the top of the closure and is in the form of a circular disc.

Extending about the periphery of the top disc 1 is a side wall 2 formed of tubing of multiple layers wound in spiral or convolute form, with the layers adhesively secured together so as to form a rigid wall structure for the closure. The upper edge of the side wall 2 is turned inward at 3 sufficiently far to overlap the upper edge of the neck C1 of the container. This inturned portion 3 on the side wall 2 may be formed by spinning over the edge of the tubing, or pressing it inward, or in other suitable manner. The upper surface of the inturned portion 3 is adhesively or otherwise secured to the underface of the top disc 1 at the outer edge portion thereof.

Secured at the inner side of the wall 2 is a guide ring 4 of less vertical height than said wall 2, and having the upper edge thereof spaced downward from the inturned flange portion 3 to receive therebetween the periphery of a liner 5.

3

The top face of the liner is depressed at 6 around its periphery to receive therein the inturned portion 3 of the side wall, so that the upper faces of the liner and of said inturned portion, are flush and fit the underface of the top disc 1. The liner 5 may be formed of one or more laminations, and of suitable protective material for sealing securely the open end of the container when pressed downward on the neck C1. The peripheral edge of the liner 5, clamped between the upper edge of the guide ring 4 and the inturned flange 3, not only tends to hold the liner in place, in addition to the adhesive attachment thereof to the top disc 1, but also presents a neat appearance to the inside of the closure by concealing the peripheral edge of the liner.

The guide ring 4, as stated, is formed of multiple convolutions which are wound one upon another and adhesively secured together. A thread 7 is formed on the guide ring to interfit with the threaded neck portion of the container.

The guide ring 4 may be secured to the side wall 2 by adhesive or in any other suitable manner, and the relative thickness of these parts may be varied so long as they coact to form a rigid and secure side wall structure which has provision for detachably fastening the closure on the container.

If desired, the side wall structure may be enclosed within a decorating strip shown at 8 in Fig. 3 of thin paper or the like, and a similar decorating sheet 9 provided on the top disc 1. These are not required where the decorations are applied directly to the side wall and top disc, or where no decoration is required.

As illustrated in Fig. 4, the side wall 2 is turned inward at 10, if desired, over the lower edge of the guide ring 4, for greater strength or decorating purposes.

It will be evident that each part of the closure may be firmly attached to the adjoining part or parts with adhesive or other suitable binding material, so as to result in a secure and rigid structure. This substantial closure is made entirely of paper or other inexpensive non-critical material, and is capable of being manufactured at a much lower cost than has been possible heretofore. The construction is such that the closure operates correctly on fast working capping equipment with no change in the structure thereof. It may be used wherever desired for the effective sealing of containers of different types.

I claim:

- 1. A closure for a container comprising a top disc formed of fibrous sheet material, a side wall structure extending about the peripheral portion of the top disc and secured thereto and having

4

an inturned flange underlying the peripheral portion of the top disc, a liner disc extending over the inner face of the top disc beneath the flange, and a guide ring of non-metallic material secured within the side wall structure in peripheral bearing relation with the outer portion thereof and having its upper edge portion bearing against the under side of the liner disc and pressing the same in clamped relation against the under side of the inturned flange, said guide ring having screw-thread engaging means for securing the closure on the container.

2. A closure for a container comprising a top disc of laminated fibrous sheet material, a side wall of laminated non-metallic material extending about the peripheral portion of the top disc, said side wall having the upper edge portion thereof inturned beneath the top disc in abutting relation therewith and secured directly thereto, a liner disc extending over the under face of the top disc in abutting relation therewith throughout the major portion of said liner disc, and having the periphery thereof underlying the flange and secured thereto, a guide ring of non-metallic laminated material inwardly of the side wall in peripheral bearing relation with said outer wall and having the upper edge thereof bearing against the under face of the peripheral portion of the liner disc pressing the same in clamped relation against the inturned flange, said guide ring having an internal thread for detachably fastening the closure on the container.

3. A closure comprising a top disc, a side wall structure extending about the periphery of the top disc and secured thereto and having an inturned flange underlying at least a portion of the top disc, a liner disc underlying said flange in overlapping relation therewith, and a ring secured to the side wall structure on the inner side thereof with the upper edge portion of said ring bearing against the under side of the liner disc and pressing the same against the flange, said side wall structure and ring being constructed of fibrous non-metallic sheet material, said ring having the periphery thereof throughout the major portion of the height of said ring secured directly to the sidewall structure in peripheral abutting relation therewith, said ring having internal screw thread means for securing the closure on a container, said inturned flange extending inwardly an appreciable distance beyond the inner edge of the ring in position for clamping relation of the periphery of the liner disc between the mouth of the container and said flange.

WILLIAM J. KEITH.
